MULTIWAVE BAND SUPERHETERODYNE
RECEIVERWinfield R. Koch, Merchantville, N. J., assignor
to Radio Corporation of America, a corpora-
tion of Delaware

Application May 29, 1936, Serial No. 82,416

7 Claims. (Cl. 250—20)

The present invention relates to a multi-wave band superheterodyne receiver, and has for its primary object to provide a receiver of that character which provides for simultaneous wave band change in both the intermediate frequency and signal selecting circuits, to maintain a predetermined desired relation between the selected intermediate frequency and the lowest frequency in a selected receiving band of frequencies.

It is also an object of the present invention to provide a multi-wave band superheterodyne receiver having means for adjusting the tuning of intermediate frequency amplifier circuits for a differing wave-band response corresponding to predetermined wave band adjustments in the tunable signal selecting or radio frequency circuits of the receiver, whereby an improved image frequency ratio and a desired degree of selectivity is obtainable in differing wave bands covering a wide frequency or wave length range of operation for the receiver.

It is a still further object of the present invention, to provide a superheterodyne radio receiver, wherein a desired frequency relation between the intermediate frequency and the lowest frequency in a selected frequency band of operation is maintained for substantially all selected frequency bands of operation, and wherein the radio frequency coils and intermediate frequency coils constituting portions of the tuned signal circuits may be used progressively, the coils for an intermediate frequency amplifier covering one frequency band of operation for the receiver, being used as the radio or high frequency coils in the receiving circuits for the next lower frequency band of operation.

The invention will, however, be better understood from the following description, when considered in connection with the accompanying drawing, and its scope will be pointed out in the appended claims.

In the drawing, the figure is a schematic circuit diagram of a multi-wave band superheterodyne receiver embodying the invention.

Referring to the drawing, the radio receiving system illustrated comprises a radio frequency amplifier tube 5 coupled to a signal input circuit 6 through a removable coupling unit 7, comprising a primary winding 8 connected through contacts 9 with the input circuit 6 and having a tuned secondary winding 10 connected through contacts 11 with a shunt variable tuning capacitor 12 and the signal input grid 13 of the tube 5.

A grounded common chassis or return circuit lead 55 is indicated at 14. The coupling device or trans-

former 7 together with shunt trimmer capacitors represented by the capacitor 15 is removable from the circuit through the medium of the contacts 9 and 11, and may be replaced by other similar coupling devices 20, 21 and 22 which may be moved progressively into connection at the contacts 9 and 11 in the order named, as indicated by the dotted lines 23 and 24.

The coil unit 20 is located in the input circuit of an intermediate frequency amplifier device 25 and is tuned by a shunt capacitor 26 in the first intermediate frequency input circuit.

In the present example and as a preferred arrangement, the unit 22 may be tuned to respond to an intermediate frequency of 175 kc., unit 21 may be tuned to respond to an intermediate frequency of 550 kc., and the unit 20 may be tuned to respond to an intermediate frequency of 1500 kc. The unit 7 is tunable through a frequency range of 4500 to 13,500 kc. by the tuning capacitor 12, thereby providing for operation of the receiver in three frequency ranges, which may be designated as shown below:

Band	IF	RF	25
A	Kilocycle 175	Kilocycle 550-1500	10
B	550	1500-4500	15
C	1500	4500-13500	20

30
35
40
45
50
55

These frequency ranges are chosen by way of example and represent any suitable number of tuning ranges which may be chosen to cover a particular wide tuning range for a multi-wave band receiver.

It will be seen that with this arrangement, the intermediate frequency coupling unit 20, when moved into the position occupied by coupling unit 7 is tuned to the lowest frequency in the next lower frequency band, which is the B band, and the unit 7 is out of operation. At the same time, the coupling unit 21 is moved into the position occupied by the coupling unit 20 and is tuned to 550 kc. whereby for the B band an intermediate frequency of 550 kc. is provided, while the input or receiving circuit is tunable from 1500 kc. to 4500 kc.

In a similar manner, the coil 22 may be moved into the position occupied by the coil 20 shown in the drawing, while the coupling unit 21 will then occupy, by progressive movement, the position occupied by the coupling unit 7 shown in the drawing. The coupling unit 21 being responsive to 550 kc. permits tuning through the A band from

550 kc. to 1500 kc. while the coupling unit 22 responsive to 175 kc. provides the intermediate frequency amplifier input coupling unit.

It will be seen that the frequency relation is such that the intermediate frequency is maintained at a value substantially one-third of the lowest frequency in the high frequency or radio frequency receiving band to be covered. It has been found that this relation of frequencies provides for less difficulty from image and other responses in the higher frequency bands, and accordingly the present tuning range adjustment permits this desirable ratio to be maintained over a relatively wide frequency coverage.

15 Oscillator, first detector and other intermediate frequency amplifier circuits are similarly tuned and adjusted to cover the same corresponding frequency bands, in accordance with the system thus far described. In the present example, 20 the oscillator and first detector are combined in one device 30, known as a penta-grid converter having a signal input grid 31, an oscillator grid 32, an oscillator anode electrode 33, an output anode electrode 34, and a cathode 35.

25 The signal input grid is further provided with a screen 36, and is connected in circuit through contacts 37 with a tuned coupling unit or transformer 38 which in turn is connected through contacts 39 with the output circuit 40 of the radio frequency amplifier tube 5. The grid circuit is tunable through the same frequency range as the radio frequency amplifier unit 7, by means of a second variable tuning capacitor 41 corresponding to the tuning capacitor 12.

35 The oscillator circuit comprises a tuned coupling unit 43, the primary 44 of which is connected through contacts 45 with the anode electrode 33, and the secondary 46 of which is connected through contacts 47 with the oscillator grid 32 40 which is provided with the usual grid leak and capacitor 48, 49. The oscillator circuit is tuned by suitable means comprising a variable capacitor 50 and a series tracking capacitor 51, the three capacitors 12, 41 and 50 normally being connected together for simultaneous uni-control operation.

The detector-oscillator output anode 34 is connected through a lead 55 with the intermediate frequency input coupling unit 20 through contacts indicated at 56. The oscillations set up in the device 30 result from electronic coupling between the oscillator frequency and the incoming signal frequency as is known and understood, to provide the desired intermediate frequency of 1500 kc. The oscillator coupling unit 43 therefore is tunable to a frequency differing from that to which the coupling units 37 and 38 are tuned, by the amount of the selected intermediate frequency.

60 With this arrangement, the coupling unit between the radio frequency amplifier 5 and the first detector 30 may be replaced in the same manner as coil switching arrangement hereinbefore described, by a coupling unit 60 forming the second stage coupling unit of the intermediate frequency amplifier between the first stage intermediate frequency amplifier 25 and a second stage or detector device indicated at 59. In the present example, the device 59 is a second detector 65 and is provided with suitable output coupling means 62 and output circuit 63 for supplying audio frequency signals to an amplifier 64 and a suitable output device such as the loudspeaker 65.

The coupling units 7 and 38 are substantially 75 the same in tuning range and frequency response,

and likewise, the coupling units 20 and 60 are the same since they are tuned to the same intermediate frequency, the capacitor 26 and a capacitor 61 being used to adjust the coupling units to the desired resonance point for use in the intermediate frequency amplifier.

For the second stage or detector B and A bands, coupling units indicated at 66 and 67 are provided to correspond to the first stage coupling units 21 and 22, respectively, and are tuned respectively 10 to the same frequencies. The wave band changing operation therefor is the same as that described for the first stage intermediate frequency amplifier and the input circuit of the receiver or radio frequency stage.

15 The switching contacts for the coils or tuning units 60, 66 and 67 in the intermediate frequency amplifier are indicated at 70 and 71, and in connection with the coils 20, 21 and 22, the output contacts therefor are indicated at 72. The coils 20 7, 20, 21 and 22 are therefore moveable along the line 23 and 24 to carry the coils 20, 21 and 22 progressively through the intermediate frequency contacts 56 and 72 and the high frequency or signal input contacts 9 and 11. In the present 25 example, the coupling unit 22 rests at the position occupied by the unit 20 between the contacts 56 and 72 for the A band operation in the same manner that the coil 7 initially rests in the position shown between the contacts 9 and 11 and 30 does not make contact with any other circuits in the three band arrangement shown. Other similar bands may be provided by additional coupling units movable into contact as described for those shown.

35 Similarly the coils or coupling units 38, 60, 66 and 67 are movable in the direction indicated by the dotted lines 73 and 74, to effect the same changes simultaneously with the wave band changes above described.

40 Since the oscillator comprises a separate circuit tunable to a differing frequency, separate coupling units to be substituted for the unit 43 are indicated at 68 and 69. It will be noted that for the A band a coupling unit for the oscillator 45 is not required since there is no corresponding stage in the intermediate frequency amplifier with which the oscillator coils are progressively interchangeable.

45 From the foregoing description it will be seen, 50 that in a superheterodyne receiver having a tunable radio frequency amplifier stage and a tunable first detector or mixer stage coupled thereto, and responsive to the same selected signal frequency range, and having an intermediate frequency 55 amplifier comprising two tuned stages utilizing duplicate coupling units therein and also tuned to the same intermediate frequency, the progressive utilization of the intermediate frequency amplifier coils or coupling devices as the signal input 60 and mixer tuning units in the next lower frequency receiving band is possible a desirable arrangement resulting in a saving of coupling units or windings and simplifying the switching operation. The latter operation may be made progressively by any suitable means for carrying the various coupling units progressively between the contacts of the fixed circuits to be associated therewith. The number of oscillator coils is one less than the number required for the other 70 circuits to be provided in the switching operation.

75 This system also has the further advantage that there is less radiation from the receiving system because the antenna circuit or input circuit is tuned to a greater frequency difference 75

from the oscillator and there is less tendency for the oscillator frequency to be affected by the tuned circuit which supplies signals to the first detector or frequency changer device, particularly when the oscillations and signals are mixed electronically as in the present example.

Furthermore, the total number of component circuit elements required is smaller than for the usual type of multi-wave band receiver wherein the intermediate frequency amplifier if adjusted in frequency, requires a separate series of coupling units or tuning means.

The main advantage, however, lies in the fact that desirable frequency relation between the intermediate or signal frequencies and the intermediate frequency may definitely be maintained throughout a relatively wide tuning range of operation comprising a plurality of frequency bands, without requiring a plurality of intermediate frequency amplifiers and without resorting to a compromise in the intermediate frequency for reasonable performance in a plurality of different signal receiving bands.

A fixed intermediate frequency is not only too high in frequency for best selectivity and tracking in the broadcast band but is too low in frequency and too selective for receiving short waves. With the present arrangement this disadvantage is overcome without introducing the additional disadvantage of complicated coils and additional circuit components and tuning means.

In the present system, wherein the radio frequency coils for each band are used as the intermediate frequency coils for receiving the next higher band, the intermediate frequency is maintained at a desired value of substantially one-third the frequency of the lower limit of the band to be covered while utilizing a minimum of additional circuit elements. The performance of a receiver utilizing this system thereby is improved through each of the several bands of a wide frequency range.

I claim as my invention:

1. In a superheterodyne receiver having a plurality of tunable high frequency signal selecting circuits, and a plurality of intermediate frequency amplifier circuits, the combination of means for adjusting the tuning of the intermediate frequency amplifier circuits for differing wave band response corresponding to a predetermined wave band adjustment in said tunable signal selecting circuits, said means comprising a plurality of tunable coupling units supported for progressive insertion in the intermediate frequency amplifier circuits and the signal receiving circuits in adjusting the response of the receiving system from a higher frequency band to a lower frequency band.

2. A radio receiver in accordance with claim 1 further characterized by the fact that the intermediate frequency amplifier coupling units for a predetermined frequency band are responsive to a frequency substantially $\frac{1}{3}$ of the lowest frequency in a selected signal band of frequencies to be received through the signal selecting circuits.

3. In a multi-wave band superheterodyne receiver, the combination of a plurality of tunable signal receiving circuits, a plurality of intermediate frequency amplifier circuits, and means providing a plurality of coil units for said circuits for each wave band to be covered by said receiver, said units being supported for progressive insertion in the said receiving circuits and said intermediate frequency amplifier circuits, the coils for

the intermediate frequency amplifier circuits in one tuning range providing the coils for the signal receiving circuits in the next lower frequency tuning range.

4. In a superheterodyne receiver, the combination of means for selectively adjusting the tuning range of the intermediate frequency and high frequency signal receiving circuits in predetermined fixed frequency relation to each other through a plurality of differing frequency bands, said means including and being adapted for progressively utilizing a series of progressively insertible tuning units for said circuits, first in an intermediate frequency circuit, and then in a high frequency signal selecting circuit in the next lower band of signal frequencies to be received.

5. In a superheterodyne receiver having a plurality of tunable high frequency signal selecting circuits, and a plurality of intermediate frequency amplifier circuits, a combination of means for progressively changing the frequency response range of said signal selecting circuits in a plurality of differing frequency ranges, means for progressively changing the frequency response of said intermediate frequency amplifier circuits, said signal selecting circuits and said intermediate frequency amplifier circuits each having contacts and a series of tunable coupling units supported for progressive movement in unison between the contacts of said intermediate frequency amplifier circuits and the contacts of the high frequency signal selecting circuits, the intermediate frequency coupling units for a higher frequency receiving range being tuned substantially to the lowest frequency in the next lower frequency receiving range for said signal receiving circuits, whereby said tuning units are progressively operable in the signal selecting and intermediate frequency amplifier circuits.

6. In a superheterodyne radio receiver having a high frequency amplifier and an intermediate frequency amplifier, the combination therewith of means providing a coupling coil system for said amplifiers comprising a series of coupling coil units supported for movement in unison progressively from connection with the intermediate frequency amplifier circuits into connection with the high frequency amplifier circuits thereby to change the tuning range of the receiver, and said tuning units being adjusted to provide a predetermined frequency relation between a selected intermediate frequency and the lowest frequency in the tuning range of the high frequency amplifier circuit throughout the frequency range of operation of the receiver, whereby a desired image frequency ratio between received signal and the intermediate frequency is maintained and a predetermined degree of selectivity is provided throughout the tuning range of the receiver.

7. In a superheterodyne receiver, the combination of a radio frequency amplifier having a high frequency coil system comprising a plurality of movable coil units for adjusting the tuning range thereof, said coil units being supported for progressive insertion into and removal from said radio frequency amplifier and an intermediate frequency amplifier therefor having amplifying circuits adapted to receive from the radio frequency amplifier at least one of said tuning units in circuit connection therewith as the frequency determining means therein in at least one higher frequency range of operation following the use of said unit in the preceding higher frequency range for the radio frequency amplifier.
